UNITED STATES PATENT OFFICE.

HAROLD F. ELLIOTT, OF PALO ALTO, CALIFORNIA, ASSIGNOR TO AUGUSTUS TAYLOR,
OF SAN FRANCISCO, CALIFORNIA.

RADIOTELEGRAPHY.

1,352,883.

Specification of Letters Patent. Patented Sept. 14, 1920.

Application filed March 23, 1920. Serial No. 368,193.

To all whom it may concern:

Be it known that I, HAROLD F. ELLIOTT, a citizen of the United States, and a resident of Palo Alto, county of Santa Clara, and 5 State of California, have invented certain new and useful Improvements in Radiotelegraphy, of which the following is a specification.

The invention relates to signaling and particularly to means for signaling with arc radio transmitters.

An object of the invention is to provide means for signaling by interrupting and re-establishing the arc.

15 Another object of the invention is to provide signaling means of the above mentioned type in which all moving parts are at earth potential.

The invention possesses other advantageous features, some of which, with the foregoing, will be set forth at length in the following description, where I shall outline in full that form of the invention which I have selected for illustration in the drawing accompanying and forming part of the present specification.

The drawing is a diagrammatic representation of one form of signaling system of my invention.

30 The transmission system comprises a Poulsen arc oscillation generator 2, which is grounded on the negative side and connected on the positive side to the antenna 3 through the variable inductance 4. Direct current is supplied to the arc by the generator 5, and 35 combined magnetic and choke coils 6 are arranged in the positive lead from the generator, so that the arc is subjected to a strong transverse magnetic field. The arc is formed 40 between the anode 7 and the cathode 8 inclosed in the chamber 10.

Shunting the arc is a circuit containing a resistor 9 and means for opening and closing the circuit. The value of the resistance 9 is preferably so adjusted that the load on the generator 5 remains the same when the arc 45 is burning and when the shunt circuit is closed. The means for opening and closing the shunt circuit comprises a stationary electrode 12 connected to the anode 7 through the resistor 9, which electrode is arranged within the arc-chamber adjacent the anode. Disposed adjacent the electrode 12 is a movable electrode 13 which is connected to the 50 cathode 8 or to the grounded side of the gen-

erator, the electrode 13 being also wholly or partly disposed within the arc chamber. Means are provided for moving the electrode 13 to open and close the shunt circuit, in the present instance the electrode being moved 60 by a signaling key 14 connected to the electrode by the link 15 and lever 16. The electrode 13 is normally held in contact with the electrode 12 by a spring 17 so that when the key is depressed, the electrodes 12 and 13 are 65 separated. As the resistance circuit is opened, an arc is produced between the electrodes 12 and 13, and this arc is blown into contact with the electrodes 7 and 8 by the magnetic field, thereby igniting the main 70 arc.

By this arrangement of parts, the movable electrode and all movable parts are at earth potential, thus overcoming the difficulty of insulating them from earth and also permitting 75 the adjustment of the movable electrode without danger.

I claim:

1. In an arc radio generator, an anode and a cathode between which an arc is formed, a 80 stationary electrode arranged adjacent the anode and connected thereto, a resistor in the circuit between the stationary electrode and the anode, a movable electrode arranged adjacent the stationary electrode and connected 85 to the cathode and means for moving the moving electrode to make and break contact between the electrodes.

2. In an arc radio generator, an anode and a cathode between which an arc is formed, a 90 resistance circuit shunted around the arc, a pair of electrodes in said circuit having their points of contact adjacent the arc gap and means for separating said electrodes where- 95 by an arc is formed which ignites the arc be- tween the anode and cathode.

3. In an arc radio generator, an anode and a cathode having an arc gap between them, means for subjecting the arc gap to a strong transverse magnetic field, a resistance circuit 100 shunting the arc and a pair of separable electrodes in said circuit disposed with their points of separation in the magnetic field ad- jacent the arc gap.

4. In an arc radio generator, a chamber 105 inclosing an anode and a cathode having an arc gap between them, a source of current supply connected to the anode and cathode, means for subjecting the arc gap to a strong transverse magnetic field, a stationary elec- 110

trode arranged in the chamber adjacent the anode and connected to the anode, a resistor in the circuit between the stationary electrode and the anode, a movable electrode 5 connected to the cathode and arranged within said chamber, the points of contact of said electrodes being in the magnetic field and adjacent the arc gap, and means for moving the movable electrode to open and 10 close the resistance circuit, opening of the resistance circuit causing an arc between the

electrodes which is blown by the magnetic field into the arc gap, igniting the arc between the anode and cathode.

In testimony whereof, I have hereunto set 15 my hand at Palo Alto, California, this 12th day of March, 1920.

HAROLD F. ELLIOTT.
